UNITED STATES PATENT OFFICE.

WALTER S. LANDIS, OF NIAGARA FALLS, NEW YORK, ASSIGNOR TO AMERICAN CYANAMID COMPANY, OF NASHVILLE, TENNESSEE, A CORPORATION OF MAINE.

METHOD OF AND APPARATUS FOR FIXING NITROGEN.

1,103,062.

Specification of Letters Patent.

Patented July 14, 1914.

Application filed April 3, 1914. Serial No. 829,387.

To all whom it may concern:

Be it known that I, WALTER S. LANDIS, a citizen of the United States, and residing at Niagara Falls, in the county of Niagara Falls and State of New York, have invented certain new and useful Improvements in Methods of and Apparatus for Fixing Nitrogen; and I do hereby declare the following to be a full, clear, and exact description of the invention, such as will enable others skilled in the art to which it appertains to make and use the same.

This invention relates to a method of and apparatus for fixing nitrogen and has for its object to lessen the cost of as well as the time heretofore required to commercially produce calcium cyanamid.

With these and other objects in view the invention consists in the novel steps constituting my process and the novel apparatus hereinafter more fully disclosed and particularly pointed out in the claims.

Referring to the accompanying drawings forming a part of this specification, in which the figure is a diagrammatic sectional view of a can for making cyanamid built in accordance with my invention, 1 indicates the outer shell of any suitable construction, 2 the inner vessel of conducting material for holding calcium carbide, 3 the carbide with which the vessel 2 is charged, 4 a resistor buried directly in the mass of carbide, 5 the upper end of the resistor which is conveniently enlarged and extended above the vessel 1, 6 and 7 the lead wires, 8 any suitable cover for said outer vessel 1, 9 an opening for the admission of nitrogen gas and 10 any suitable vent opening.

Prior to my invention the process of making calcium cyanamid comprised the reacting on carbide by heating to a suitable temperature a small portion of the carbide and supplying nitrogen as the reaction proceeded. In carrying out this old process a central core of carbide of greater or less dimensions was provided and a small resistor was inserted in this core for the purpose of heating said core to the reacting temperature. The core was also so constructed as to permit a free flow of nitrogen around the carbon resistor. But it is a well known fact that it is practically impossible to get absolutely pure nitrogen, and that the usual impurities carried by this gas have an oxidizing effect on the carbon resistor at the

temperatures to which it must be raised. A rapid deterioration of said resistors is a direct result of these impurities, and it is a further known fact, that the cyanamid industry is, as a consequence, forced to replace these resistors sometimes as often as several times a day, thus not only entailing a loss of resistors but the loss of considerable time, as well as experiencing serious interruptions of the heating of the carbide. Further experience has taught me that when the carbide is heated to a reacting temperature in the presence of nitrogen it stands up as a hard, impervious mass of cyanamid around the core, the thickness of which mass will increase as the process continues. This said impervious mass surrounding the core so greatly hinders the feeding of the nitrogen therethrough to fresh carbide, that in reality it renders the core useless, for in fact, the core cannot furnish a means for facilitating the feeding of the nitrogen after the reaction has proceeded for some time, as has been believed heretofore. As a matter of fact, observation has convinced me, that the nitrogen is fed to the carbide mass after the process is well under way, not through the core at all, but from the outside of the mass toward the center. In other words, I have discovered that an open central core in the can is useless, and that I can avoid the above objections and improve the process of commercially producing cyanamid by embedding the carbon or other resistor directly in the carbide mass as above indicated.

I may use the same form of resistor as heretofore, but by electrically connecting its lower end to the can 2, and by permitting its upper end 5 to project outside the vessel, I facilitate the electrical connections, and further eliminate the oxidizing effects of the impurities carried by the nitrogen, except at the point 11 between the vessels 1 and 2. The resistor, however, at this point is at a lower temperature and has a larger cross section, so the oxidizing effects may be neglected. Actual experience has proved that this method of igniting the carbide is just as efficient as is the old method, and that it further avoids the necessity of changing the resistors at all during the nitration of the furnace charge. In fact, this method easily saves six or eight resistors and the losses attendant upon the changing of the same during each run.

This method further simplifies the construction of the furnace, since no provision need be made for changing the resistors in a hot furnace as has been the case heretofore. In 5 this new method of ignition the rate of reaction is, as heretofore, controlled by the rate at which the nitrogen reaches the reacting surface. But since the finely ground carbid offers a great resistance to the flow 10 of nitrogen, the reaction itself is slow and therefore the total heat given off is not as high as it would otherwise be. Accordingly I prefer in both the old and new process to introduce heat to the mass from an 15 outside source in order to facilitate the nitrification. This may be conveniently accomplished by maintaining a high temperature in the resistor throughout the process.

What I claim is:—

20 1. The process of forming nitrogen compounds through the reaction of nitrogen upon carbid, which consists in burying the resistor used for supplying heat to the charge directly in the mass of the said carbid, and out of direct contact with the circulating excess nitrogen in said charge; and raising said resistor to a temperature sufficient to cause the desired reaction, while 25 feeding nitrogen to the charge, substantially as described.

2. The process of fixing nitrogen which consists in providing a suitable charge of calcium carbid; burying a resistor directly in the mass of said charge and out of direct 5 contact with the circulating excess of nitrogen through the said charge; preventing destruction through oxidizing effects of said resistor outside of said charge; and raising 30

said resistor to a temperature sufficient to cause the desired reaction, while feeding 40 nitrogen to the charge, substantially as described.

3. In an apparatus for fixing atmospheric nitrogen, the combination of a suitable container adapted to hold a charge of 45 carbid; a resistor entering said container and adapted to be directly buried in said charge out of direct contact with the circulating excess of nitrogen through the interstices of said charge; means for decreasing 50 the rate of destruction of said resistor outside of said charge through oxidizing actions; means for passing a current of electricity through said resistor; and means for feeding nitrogen to said charge, substantially as described.

4. The process of fixing nitrogen which consists in providing a suitable charge of calcium carbid; burying a resistor directly 60 in the mass of said charge and out of direct contact with the circulating excess of nitrogen through the said charge; preventing the destruction through oxidizing effects of said resistor outside of said charge; raising said resistor to a temperature sufficient to cause 65 the desired reaction, while feeding nitrogen to the charge; and continuously supplying heat from an outside source to said mass during the process of nitrification, substantially as described.

In testimony whereof I affix my signature, in presence of two witnesses.
